US00D794889S

(12) **United States Design Patent** (10) **Patent No.:** **US D794,889 S**
(45) **Date of Patent:** **** Aug. 15, 2017**

(54) **CLEANSING ARTICLE**

- (71) Applicant: **The Procter & Gamble Company**, Cincinnati, OH (US)
- (72) Inventors: **Lauren May Althaus**, Cincinnati, OH (US); **Joshua Scott Suhre**, Cincinnati, OH (US)
- (73) Assignee: **The Procter & Gamble Company**, Cincinnati, OH (US)
- (**) Term: **15 Years**
- (21) Appl. No.: **29/530,746**
- (22) Filed: **Jun. 19, 2015**
- (51) LOC (10) Cl. **04-01**
- (52) U.S. Cl. **USPC D32/40**
- (58) **Field of Classification Search**
USPC D32/40-42, 46-49; D8/33, 47, 90, 93;
D4/118, 199; D24/146-147
CPC A47L 1/06; A47L 13/24; A47L 15/0081
See application file for complete search history.
